UNITED STATES PATENT OFFICE.

WILLIAM R. COCHRAN, OF DELPHOS, OHIO, ASSIGNOR OF ONE-HALF TO ALBERT ESTERLINE AND GEORGE W. SHERER, BOTH OF FORT WAYNE, INDIANA.

OIL-BURNER.

1,310,283.

Specification of Letters Patent.

Patented July 15, 1919.

Application filed October 29, 1918. Serial No. 260,082.

To all whom it may concern:

Be it known that I, WILLIAM R. COCHRAN, a citizen of the United States, and a resident of Delphos, in the county of Allen 5 and State of Ohio, have invented certain new and useful Improvements in Oil-Burners; and I do hereby declare the following to be a full, clear, and exact description of the invention, such as will enable others skilled in 10 the art to which it appertains to make and use the same.

My invention relates to an improvement in oil burners adapted for attachment to heating and cook stoves, the object being to provide a burner that will be of few parts, simple in construction and adapted to be readily applied within the fire pot of any ordinary heating or cook stove, and it consists in the 15 details of construction as will be more fully 20 explained and pointed out in the claims.

In the accompanying drawings, Figure 1 is a view in elevation of my improved device. Fig. 2 is a plan view of the same, and Fig. 3 is a view in end elevation.

25 1 represents the base of the burner attachment, comprising a rectangular metal plate provided at its front and two ends with a continuous integral flange 2 sufficiently high to hold any oil that may overflow at the start, 30 and also provided at its rear side with the integral back plate 3 which preferably terminates slightly below the top of the air pipes as shown in Fig. 1. Base plate 1 is also provided adjacent each end with an air opening 4, preferably circular as shown, and centrally with the saucer shaped deflector 6, the latter being cast integral with base plate 1.

35 5 are the combined air supply pipes and 40 mixing chamber, comprising two end members 5^a which rest at their open ends on member 1 over and around the openings 4 therein, and the central member 5^b which is shorter than the end members 5^a and terminates in the vertical plane of the deflector 6 and slightly above the top of the latter, so 45 that the mixed air and vapor as it issues from the lower open or burner end of the mixing chamber, strikes the upper concave 50 face of the deflector and is deflected circumferentially from the same. The air pipes and mixer 5 are hollow throughout their length for the free passage of the air which enters at the two ends thereof, and is sup-

ported against accidental displacement by 55 the circular flange 7 surrounding the openings 4 and forming in effect recessed seats for the lower ends of the members 5^a, and also by the oil pipe 8, which is secured to the back plate 3 and passes through the part 5 60 at the meeting point of the air passages in the two members 5^a. The oil pipe 8 is secured to back plate 3 and communicates with the duct 9 formed in an enlargement 10 cast integral with back plate 3. The duct 9 is 65 open at its lower end at the rear of the back plate as shown in Fig. 3, for the attachment of the oil supply pipe 11 which is provided with a valve 12 for cutting off and also for controlling the supply of oil to the pipe 8. 70 Pipe 8 projects horizontally through the mixing chamber 5 from the rear, and is closed at its outer end and provided on its lower side with one or more holes or slots for the escape of the oil or vapor that may 75 be generated in the pipe 8 or duct 9.

The base 1 is adapted to be entered and supported in the fire pot of any ordinary coal or wood burning stove, and is connected up to the oil supply pipe 11 which supplies 80 the oil from a reservoir located adjacent the stove.

By opening valve 12 the oil enters duct 9 and flows into pipe 8 and drips into the saucer shaped deflector 6. By igniting the oil 85 within the deflector, the heat therefrom soon heats up the oil in pipe 8 so that the latter vaporizes and ignites, as it issues from the open end of mixing chamber 5^b and by the time the oil in the saucer-shaped deflector 6 90 has been consumed, the heat from the burning vapor and air is sufficient to continue the vaporization of the oil in pipe 8 and duct 9. As the open or burner end of the mixing chamber begins to heat up, a current of air is 95 induced up through the openings 4 in body member 1, through members 5^a of the air supply pipe to the mixing chamber 5^b. As the walls of the mixing chamber and the adjacent parts of member 5 become highly 100 heated by the burning vapor and air, the latter in its passage to the mixing chamber also becomes highly heated and in a condition to thoroughly commingle with the vapor generated in the pipe 8. The mixed air and vapor 105 burning at the burner end of the mixing chamber is projected against the saucer shaped deflector and is deflected laterally.

thereby into a ring like flame which is sufficiently intense for cooking or heating purposes.

The attachment being a unitary structure 5 independent of the stove, can be removed and replaced in the fire pot of a stove without the employment of skilled labor, and when in place can rest on the grate or grate supports or if desired on brick or other supports resting on the grate.

It is evident that slight changes might be resorted to in the relative arrangement of parts shown and described without departing from the spirit and scope of my invention, hence I would have it understood that I do not wish to confine myself to the exact construction and arrangement of parts shown and described, but,—

Having fully described my invention what 20 I claim as new and desire to secure by Letters-Patent, is:

1. An oil burner attachment for stoves consisting of a base member having air openings through the same adjacent its ends, a 25 burner member having upwardly extending air ducts at its ends which terminate centrally in a downwardly projecting burner member open at its lower end, an oil pipe projecting into the burner member over the 30 burner opening therein, and a saucer shaped deflector below and in the vertical plane of the burner opening, the said deflector be-

ing of greater diameter than the burner opening.

2. An oil burner attachment for stoves 35 consisting of a base member having a continuous edge flange, and air openings adjacent its ends, a burner member having air ducts in communication with the openings in the base member and terminating in a 40 downwardly projecting centrally located burner member, a saucer shaped deflector on the base member and under the lower end of the burner member, and an oil pipe discharging into the burner member in the vertical 45 plane of the burner opening.

3. An oil burner attachment for stoves consisting of a flat base member having an integral back plate, a burner member having two air ducts at its ends which meet at the 50 center and form a mixing chamber which projects downwardly and is open at its lower end, an oil pipe carried by the back plate and communicating with an oil duct in said plate, the oil pipe projecting into the mixing chamber, and a deflector located below the lower open end of the mixing chamber.

In testimony whereof I have signed this specification in the presence of two subscribing witnesses.

WILLIAM R. COCHRAN.
